Patented May 1, 1923.

UNITED STATES PATENT OFFICE.

ARCHIE NOEL JETTE, OF ANACONDA, MONTANA

CONSTRUCTION OF SMELTING FURNACES.

Original application filed August 10, 1920. Serial No. 402,556. Divided and this application filed January 3, 1921. Serial No. 434,760.

To all whom it may concern:

Be it known that I, ARCHIE NOEL JETTE, a citizen of the United States, residing at Anaconda, in the county of Deerlodge and State of Montana, have invented certain new and useful Improvements in the Construction of Smelting Furnaces, of which the following is a specification.

This invention relates to metallurgical smelting furnaces of the reverberatory type, and in particular to reverberatory copper smelting furnaces.

The main object of this invention is a construction affording a support for the main arch and also a tie between both ends of the furnace.

The more special objects will appear from the specification and the accompanying drawings in which

20 Fig. 1 is a side elevation, parts being broken away, of a furnace construction embodying the invention;

Fig. 2 is a perspective view, on a larger scale, of the firing end of the furnace; and

25 Fig. 3 is a front elevation of the other end thereof.

In Fig. 1, 10 represents a furnace of 100 feet or more in length and 11 the arched roof. At the metal-discharge end is a secondary chamber 12 more fully described in my application Serial No. 402,556 filed August 10, 1920, of which this application is a division.

The invention consists chiefly in a skew-back plate 13 extending along each side of the furnace from end to end and secured at its ends to suitable frame work bearing against the ends of the furnace.

The skew-back plates 13 may be of any width desired, even to the extent of covering the whole furnace side and are made of beams or girders secured together. They bear against the sides of the furnace and are held against transverse movement by vertical beams 14 and buck-stays.

The connections with the frame work bearing against the ends of the furnace is more clearly shown in Figs. 2 and 3.

At the firing end of the furnace, the skew-back plates are braced by vertical portions 15 and inclined portions 16 forming triangles with the plates 13.

Across the end of the furnace extend 17 beams and against these transverse beams 18 bear vertical beams 18. These vertical

beams are anchored in a concrete base and are connected near their upper ends to the skew-back plates 13 in any suitable manner.

At the opposite end the furnace terminates in the secondary chamber 12. To afford a strong support against this end of the furnace, beams 19 are anchored in concrete and bear against the chamber or culvert 12. Across the upper ends of these beams 19 extends a beam 20 connected by tie rods or 60 beams 21 to vertical beams which may be the end beams of the rows of beams 14 above referred to. To these beams are secured the skew-back plates 13, directly at their ends and indirectly through the braces 22.

It is understood that the structure bearing against the ends of the furnace and the form of connection between these structures and the skew-back plate may be modified in various ways within the scope of the invention.

In the old design and construction of reverberatory furnaces where tie rods over the furnace top were employed to tie one end of the furnace to the other end, many disadvantages were experienced. The construction was expensive, necessitating a large number of iron rods of large diameter, which rods occupied space over the top of the furnace and thereby interfered with repairs to 85 the furnace roof.

With the proposed construction the tie-rod system is eliminated and a cheap and strong tie member obtained. At the same time valuable head room or working space is 90 provided for repairs to the furnace roof. Furthermore additional support to the main arch is provided.

I claim:

1. The combination with a reverberatory furnace, of frame constructions bearing on opposite ends of the furnace, lateral skew-back plates for supporting the arch of the furnace and connected with the said frame constructions to serve as ties therebetween.

2. The combination with a reverberatory furnace, of frame constructions bearing on opposite ends of the furnace, lateral skew-back plates for supporting the arch of the furnace and means for interconnecting the skew-back plate and the frame constructions for placing the former under tension to serve as ties between the latter.

3. Arrangement according to claim 2 in which each frame construction includes a

plurality of frame elements extending transversely of the furnace end in parallel relation and beams bearing against the said frame elements and connected to the skew-back plates.

4. Arrangement according to claim 2 in which the interconnecting means includes braces.

5. The combination with a reverberatory furnace having at one end a secondary chamber extending above the main arch, a frame construction bearing against the end

of the secondary chamber, a frame construction bearing against the opposite end of the furnace, lateral skew-back plates and means for interconnecting the skew-back plates and said frame constructions including braces extending from the skew-back plates to points above the secondary chamber and tie rods for interconnecting the braces and the frame construction bearing against the end of the secondary chamber.

In testimony whereof, I affix my signature.

ARCHIE NOEL JETTE.
